POLE INCISING MACHINE

Hugh B. Tinling, Spokane, Wash.

Application June 12, 1947, Serial No. 754,124

3 Claims. (CL 144—2)

1

It is the principal purpose of my invention to provide a simple effective machine of this character wherein poles to be incised or punched are advanced and rotated beneath a large toothed disk or wheel set at the proper angle to form a spiral path of incisions as the pole is advanced. The incisor disk is freely supported to be turned by the pole and is of such size and weight as to make the necessary depth of cut without additional force being applied.

In the treating of poles that are to be used where rot and decay is an important factor, it is customary to apply a preservative to that part of the pole which is subject to the greatest damage by decay. For example, in telephone and power line poles, the large end of the pole is usually treated for a distance of several feet. In order for the preservative to penetrate into the wood fibers, it is the custom to form incisions through the surface of the pole at short intervals. The cuts are usually made by a chisel-like tool with the edge thereof directed lengthwise of the pole so as to break as few fibers as possible in order to get the proper penetration of preservative with a minimum weakening of the pole itself.

According to my invention, I utilize a large diameter of wheel or disk to mount a series of teeth for making the incisions in the pole. The diameter of the disk is several times the pole diameter being treated, in order that the tilting of teeth with respect to the pole as the disk and pole rotate, will be at a minimum such as to prevent tearing or breaking of the fibers to a substantial degree. I support the disk carrying the teeth upon a lever arm, which is normally free to allow the weight of the disk to ride on the pole. The lever arm is provided with a hydraulic cylinder for raising the disk out of the way and allowing a treated pole to be discharged and a new pole to be moved into position.

The novel features that I consider characteristic of my invention are set forth with particularity in the claims. The invention itself, however, both as to its organization and its method of operation, together with additional objections and advantages thereof, will be best understood from a description of a specific embodiment when read in connection with accompanying drawings, in which:

Figure 1 is a plain view of an incising machine embodying my invention;

Figure 2 is a fragmentary view illustrating the position of the incised part of the pole when a pole is set in the ground;

Figure 3 is a perspective view of a carriage used to support the end of the pole as it is being drawn through the machine after treatment;

Figure 4 is a side view of the incising machine;

Figure 5 is a fragmentary view in side elevation of a portion of the incising disk and;

Figure 6 is an edge view of a portion of the incising disk following the manner of mounting the teeth on the disk.

2

Referring now in detail to the drawings my invention, as shown, is adapted to prepare the surface of a pole 10 for treatment with a preservative by forming on the surface of the pole, over a substantial length thereof, a series of shallow incisions shown at 11 in Figure 2. This method of preparing the pole surface for the preservative is well-known in the art, but it has heretofore presented considerable difficulty. Many machines of large and cumbersome construction have been built for the purpose of making the necessary incisions. However, according to my invention, I provide a simple mechanism by which the poles may be fed endwise to the incising device, and for that period of time necessary to make the incisions, the poles are advanced spirally while a large disk several times the diameter of the pole, or an equivalent device carrying the necessary incising teeth, is allowed to ride freely on the pole to make the incisions and then is lifted to permit removal of that pole and the insertion of a new one.

The machine as shown best by Figures 1 and 4 comprises two power-driven toothed supporting wheels 12 and 13 which are arranged at a slight angle to a plane perpendicular to the axis of the pole as it is advanced through the machine. Carriages such as 14 running on rails 15 and 16 move the poles to and from the machine. The wheels 12 and 13 are driven by motors 17 and 18 so that they spin the pole 10 and, at the same time, advance it in a spiral direction. The incisor proper comprises a large wheel 20 which is mounted upon a pair of arms 21 by an axle 22. The arms 21 are pivoted on a bracket 23 by a pivot pin 24, the bracket 23 being secured on an upright wall 25. In order to lift the disk 20 I provide an hydraulic cylinder 26 which has its piston 27 secured by a pin 28 to the arms 21. The cylinder 26 is mounted on a pedestal 29 by means of pins 30 on the cylinder and yokes 31 on the pedestal. A conduit 32 for pressure fluid to the cylinder may be supplied from any suitable source of fluid under pressure as will be readily understood. A two way valve 40 is connected in the conduit 32 to control the fluid supply to the cylinder 26.

The cylinder is coupled to the head 27a of the piston 27 by a pair of links 43 and 44 which are pivoted on the piston head and cylinder respectively and pivoted together by a pin 45. This limits the rise of the piston. The pin and yoke construction shown allows the cylinder to swing about the pins 30 as an axis to accommodate the slight angular movement produced by the swinging of the arms 21 around their pivot pin as the disk 20 is raised and lowered. The disk 20 is braced by a brace rod 41 that is pivoted on a bracket 42 on the wall 25 at the same level as the bracket 23.

The disk 20 comprises preferably a large circular metal plate. On the opposite sides of this plate there are rows 33 and 34 of chisels. The chisels in the row 33 are staggered with respect to those in the row 34 as shown by Figures 5 and 6.

Each of the chisels has its cutting edge 35 formed by tapering the tip of the chisels so that the cutting edge is at substantially right angles to the disk 20. The chisels are welded in place as indicated at 39 on the disk so that if one of them becomes broken it may be removed and a new one welded in its place.

The carriage 14 is supported by suitable wheels 36 and 37 on the rails 15 and 16. The carriage has a bar 38 at the top thereof to receive the pole 10. It is evident that a carriage such as the carriage 14 may bring the poles to the incising machine and another carriage of like construction may be used to remove the poles. This machine, however, is often used in connection with a peeling machine so that the poles go directly from the peeler over the wheels 12 and 13 to the incising disk 20. In all cases the incising disk is held in raised position during time the pole is advanced to the point where the disk should engage the pole to make the necessary incisions in the desired length of the pole. The operator then merely shifts the valve 40 to allow the fluid in the cylinder 26 to drain out so that the weight of the incisor disk 20 will rest on the pole and extend crosswise of the pole at a slight angle from perpendicular to the pole.

The pole will be turned in a spiral manner by the wheels 12 and 13 which in turn will cause the incisor disk to rotate because of its engagement with the pole and the weight of the disk will cause the teeth on the incisor disk to penetrate the pole. After a sufficient length of the pole has been engaged by the teeth, the operator again applies fluid under pressure to the cylinder 26 thereby lifting the incisor disk away from the pole where it remains until a new pole is brought into position. Since the disk itself does not have any rotative power applied to it, it may be left in this raised position and does not provide any hazard such as would be the case were it rotated under power.

One of the distinctive advantages of this device as shown in practice, lies in the fact that the disk is several times the diameter of a pole being treated. This reduces the amounting of splintering of the fibers of the pole to a point that is not objectionable, yet, at the same time, it gives a solid mounting for the chisel teeth so that the penetration of the pole is accomplished in a uniform manner. There is, of course, some tilting of the teeth in the wood because of the small diameter of the pole itself. It is, of course, within the scope of my invention to provide the chisel teeth upon a different type of support than the disk, whereby to follow the surface of the pole even more closer. Such a support, for example, may embody a traveling belt carried in the same manner that the disk 20 is carried and caused to rotate with the pole by its weight resting on the pole.

It is believed that the nature and advantages of my invention will be understood by those skilled in the art from the foregoing description and the accompanying drawings. Having thus described my invention I claim:

1. An incising machine for poles comprising in combination a pole supporting carriage mounted to travel in a horizontal direction lengthwise of a pole thereon, toothed power driven wheels positioned to engage a pole on the carriage and set at a slight angle to a plane perpendicular to the path of movement of said carriage for turning a pole and moving it endwise simultaneously

whereby any particular point on the pole surface takes a spiral path, a toothed incisor over the path of the pole, a lever arm pivotally mounted at a point laterally spaced from the carriage to swing in a plane parallel to said wheels and supporting the incisor for vertical swinging movement, a piston supporting the arm and incisor, a cylinder for said piston, fluid supply means for the cylinder and a control valve for said fluid supply means, the incisor being mounted for rotation on said arm free to turn by engagement with the pole when lowered thereon.

2. An incising machine for poles comprising in combination a pole supporting carriage mounted to travel in a horizontal direction lengthwise of a pole thereon, toothed power driven wheels positioned to engage a pole on the carriage and set at a slight angle to a plane perpendicular to the path of movement of said carriage for turning a pole and moving it endwise simultaneously whereby any particular point on the pole surface takes a spiral path, a toothed incisor over the path of the pole, a lever arm pivotally mounted at a point laterally spaced from the carriage to swing in a plane parallel to said wheels and supporting the incisor for vertical swinging movement, a piston supporting the arm and incisor, a cylinder for said piston, fluid supply means for the cylinder and a control valve for said fluid supply means, the incisor comprising a disk of several times the pole diameter, said disk having radially projecting teeth on its periphery and being rotatably mounted on said lever arm to extend crosswise of the pole path.

3. An incising machine for poles comprising in combination a pole supporting carriage mounted to travel in a horizontal direction lengthwise of a pole thereon, toothed power driven wheels positioned to engage a pole on the carriage and set at a slight angle to a plane perpendicular to the path of movement of said carriage for turning a pole and moving it endwise simultaneously whereby any particular point on the pole surface takes a spiral path, a toothed incisor over the path of the pole, a lever arm pivotally mounted at a point laterally spaced from the carriage to swing in a plane parallel to said wheels and supporting the incisor for vertical swinging movement, a piston supporting the arm and incisor, a cylinder for said piston, links pivoted on the cylinder and piston and pivotally connected to each other to limit the lift of the incisor, fluid supply means for the cylinder and a control valve for said fluid supply means, the incisor being mounted for rotation on said arm to turn by engagement with the pole when lowered thereon.

HUGH B. TINLING.
